Dave Richardson
design for Cuban Cigar
Co. of Stamford & Stamford New Haven, Conn.

Des 794

David Hathaway, of New York, N.Y. Ass't. to
Copy, Richardson & Boynton of New York, (aforesaid)
Letters Patent N° 794, Dated May 20th 1836.

~~~~~

The schedule referred to in these Letters Patent, and making part of the same.

To all whom it may concern:

Be it known that I, David Hathaway of the City, County and State of New York, have invented or produced a new and original design for a Parlor Stove which I call the "Coral", and I do hereby declare that the following is a full, clear and exact description of the same, reference being had to the accompanying perspective drawing and the letters of reference marked thereon, making a part of this specification.

The description of my design for a parlor stove is as follows, viz; A, is the top plate, having an ornamental cover B, fitting over it; C, is the front plate having an ornamental sunk panel (a, a,) at each end, and the sliding doors with the ornaments (b, b); (c, c) are ornamental brackets at each side of the plate; D, is the blower plate, ornamented with the scrolls (d, d,) and shells (e, e); E, is the bottom and hearth plate, decorated with the shell surfaces (f,) and (g), and moulding (h). F, is the end plate having the mouldings (i) (j) and (k) on its lower end, and the ornamental panels (l, l, l,) on its upper end. G, is a leg, ornamented with the moulding (m) pendants (n) and scrolls (o).

Having fully described my design of parlor stove plates; what I claim as new and desire to secure by Letters Patent, is; the ornamental configuration of Parlor stove plates, such as herein described, and shown in the annexed drawing.
